DESIGN FOR A TEMPLATE

Harold M. Harrison, North Hollywood, Calif.

Application March 31, 1942, Serial No. 106,410

Term of patent 7 years

To all whom it may concern:

Be it known that I, Harold M. Harrison, a citizen of the United States and resident of North Hollywood, in the county of Los Angeles and State of California, have invented a new, original, and ornamental Design for a Template, of which the following is a specification, reference being had to the accompanying drawing, forming a part thereof.

I claim:

The ornamental design for a template, substantially as shown.

HAROLD M. HARRISON.
